FIG. 1

FIG. 1 is a front perspective view of a domestic scale showing my new design, the bottom thereof being supported by a narrow ring but otherwise flat and unornamented; and

FIG. 2 is a top plan view thereof.

The side opposite FIG. 1, not shown, is substantially identical thereto except for the absence of the recessed nodule or button on which an official stamp is applied.

I claim:

The ornamental design for a domestic scale, as shown and described.
